CLOSURE FOR LUBRICATORS

Bengt E. Folke, Mamaroneck, N. Y., assignor to
Nathan Manufacturing Company, New York,
N. Y., a corporation of New York

Application October 7, 1943, Serial No. 505,270

3 Claims. (Cl. 292—256)

This invention refers to improvements in closures for mechanical lubricators particularly the kind which are used on railway locomotives where they are located in positions subjected to a great amount of vibration.

It is one of the principal objects of the invention to provide a quickly detachable means for securely holding a hinged type of lubricator cover against its seat.

Another object is to provide means whereby a clamping arrangement located outside the lubricator cover serves to exert pressure on the cover at a point between the supporting seating edges so as to prevent the cover from being tilted on its seat when the clamping means are tightened.

A further object is to provide clamping means that require little space when disengaged as well as when in place holding the cover closed.

Still further objects will become apparent in the following specification and the accompanying drawings in which

Fig. 1 is a cross-sectional view of a fragmentary part of a lubricator body and its cover as heretofore in use shown in a closed position and with its clamping member in dotted lines in an open position;

Fig. 2 is a cross-sectional view of a fragmentary portion of a lubricator body and its cover embodying a preferred form of the principles of the invention, the cover being shown in a closed position;

Fig. 3 is a fragmentary cross-sectional view similar to Fig. 2 showing the cover clamping means in an open position;

Fig. 4 is a plan view of the lubricator body, shown fragmentarily in Fig. 2, and its cover, with two cover clamping means and a sealing bar holding them in place;

Fig. 5 illustrates a modified form of a clamping member in a closed position; and

Fig. 6 shows the same member in an open position.

Like numbers of reference denote similar parts throughout the several views and the following specification.

In Fig. 1 which illustrates a former method for keeping a lubricator cover closed, 10 is a lubricator body of a construction well-known in the art having a cover 11 provided with a hinge bolt 12. The cover 11 is fulcrumed on the hinge bolt 12, and in its closed position makes a tight joint against a seat 13. The cover is provided with two lugs 14 projecting from its side, each of which has a reduced rectangular terminal 15 over which a clamping yoke 16 is slipped, pivotally secured

to a pin 17 in lug 18 on the body proper. The clamping yoke has a screw 19 which serves to hold the cover against its seat. A sealing bar 20 is passed through the two terminals 15 and is held in place by a suitable seal to prevent unauthorized opening of the cover.

Inspection of this construction clearly shows that the more pressure is exerted upon the projecting lugs 14 and their extensions 15 of the cover, the more pressure will be exerted against that part of the seat 13 which is adjacent these lugs. In other words, the clamping has a tendency to tilt the cover upon its seat which causes uneven pressure against it and subsequent leakage of oil through that side of the lubricator cover farthest removed from the clamping lugs.

Now referring to the Figs. 2, 3 and 4 which embody the particular principles of the invention, 21 is a top portion of a lubricator body which has a raised seat 22 for a cover 23 engaging this seat. Cover 23 is hinged to the lubricator body with lugs 24 adapted to fulcrum about a pin 25 journaled within lugs 26. In the center of the cover a cap 27 is provided for to permit filling the lubricator with oil without opening the main cover 23 which is opened only at times when it is desired to make adjustments to the interior mechanism of the lubricator.

The cover locking means consists of a clamping member 28 having arms 29 and 30 angularly disposed with respect to each other. A slot 31 is provided for within the center of the junction of the arms 29 and 30 to accommodate a link 32 adapted to fulcrum around a pin 33 transversely through the center part of the clamping member 28. Link 32 is pivotally secured to a pin 34 fixed between two lugs 35 on the body proper. The lower arm 30 of the clamping member 28 rests upon the body of the lubricator, while the upper arm 29 is provided at its end with a screw 36 adapted to be screwed downwardly to press the cover 23 against seat 22. 37 is a sealing bar passed through registering openings in the center part of clamping member 28 and link 32. This sealing bar is provided with a suitable seal 38 preventing unauthorized removal of the bar.

Referring again particularly to Fig. 2, it will be noted that in the closed position the clamping member 28 is held in fixed relation with respect to the link 32 by means of the sealing bar 37. When the screw 36 is tightened against the cover 23, the clamping member 28, link 32 and sealing bar 37 act as one unit, and the pressure exerted by the screw at a point on top of the cover and well within the confines of the seats

between the cover and the body hold the cover securely in place.

Attention is especially drawn to the fact that by means of the clamping arrangement shown in Fig. 2 an even pressure is exerted by the cover against its seat. No tilting action is present. The fit between the cover lugs 24 and fulcrum pin 25 which serves as a hinge for the cover is of commercial character and sufficiently loose not to prevent tight closing of the cover.

When it is desired to lift the cover to an open position, the screw 36 is loosened, the seal 38 broken and the sealing bar 37 removed. This permits moving the clamping member 28 away and clear of the lubricator cover 23, as shown in Fig. 3, and the cover may then be raised by means of hand lugs 39 at the side of the cover shown in Fig. 4. Inspection of the drawings discloses that in either the closed or open positions the clamping arrangement does not project objectionably beyond the contours of the lubricator itself.

The modified arrangement shown in Figs. 5 and 6 is practically identical with that shown in Figs. 2, 3 and 4, with the exception that the lower arm of the clamping member rests against the side of the lubricator at 40 instead of the top portion of the body indicated at 41 in Fig. 2.

For matter of convenience the same numbers of reference are used in Figs. 5 and 6 as in Figs. 2 and 3.

It is understood that various changes in form, proportions, and minor details of construction may be resorted to without departing from the principles or sacrificing any of the advantages of the invention as defined in the appended claims.

What I claim as new is:

1. A latch for the cover of a lubricator body, the cover being hinged to the body and having surfaces adjacent its outer edges seating upon said body, said latch comprising an integral lug extending from said body, a link having one end pivotally secured to said lug, a clamping member pivotally secured to the other end of said link, one end of said member having means to ad-

justably engage the top of said cover while its other end contacts said body, and a removable sealing bar through said link and clamping member holding said link and member in fixed relation to each other as an integral unit, pivotally secured to said lug, when the cover is closed, preventing opening of the cover.

2. A latch for the cover of a lubricator body, the cover being hinged to the body and having surfaces adjacent its outer edges seating upon said body, said latch comprising an integral lug extending from said body, a link having one end pivotally secured to said lug, a clamping member comprising two arms angularly disposed with respect to each other and pivotally secured at their junction to the other end of said link, one arm having means to adjustably engage the top of said cover at a substantial distance away from its edges while said other arm contacts said body, and a removable sealing bar through said link and clamping member holding said link and member in fixed relation to each other as an integral unit, pivotally secured to said lug, when the cover is closed, preventing opening of the cover.

3. A latch for the cover of a lubricator body, the cover being hinged to the body and having surfaces adjacent its outer edges seating upon said body, said latch comprising an integral lug extending from said body, a link having one end pivotally secured to said lug, a clamping member comprising two arms angularly disposed with respect to each other and pivotally secured at their junction to the other end of said link, one arm having adjusting means engaging the top of said cover intermediate its outer edges at a substantial distance from the edge nearest said link while said other arm contacts said body, said other end of the link being at a level above that of said cover, and a removable sealing bar through said link and clamping member holding said link and member in fixed relation to each other as an integral unit, pivotally secured to said lug, when the cover is closed, preventing opening of the cover.
